CAN VALVE ASSEMBLING MACHINE

Alfred L. Kronquest, Syracuse, N. Y., assignor
to Continental Can Company, Inc., New York,
N. Y., a corporation of New York

Application November 4, 1936, Serial No. 109,184

20 Claims. (Cl. 113—1)

This invention relates to new and useful improvements in a machine for inserting valves in can ends, which are adapted to be used, for example, in cheese cans.

5 In the manufacture of valved cans, it is customary to provide the can end with a central vent, which is covered and normally closed by an elastic valve of rubber or the like, so that gases evolved within the can are permitted to escape. The can end is die stamped to form a circular central recess. The valve is first secured within a dished valve body with a peripheral flange, which is then forced into the recess in the can end and secured therein. An example 10 of a can end of this type is shown in Patent No. 1,950,327, issued March 6, 1934, to William F. Punte.

An object of the present invention is to provide a machine in which the previously formed 20 valve body with the valve therein is automatically inserted and secured in the previously formed can end.

A further object of the invention is to provide 25 mechanism which may be associated with a conventional type of punch press for assembling and securing the valve bodies within the recessed can ends.

It is also an object of the invention to provide 30 automatic feeding mechanism for the can ends and the valve bodies, in connection with the mechanism for assembling the same.

The invention also includes various details 35 of construction and novel combinations, the purpose and operation of which will be specifically explained in connection with the accompanying drawings and subsequently claimed.

In the drawings,—

Fig. 1 is a side elevation of a punch press with 40 the invention mounted thereon.

Fig. 2 is a plan view of the dies which are 45 mounted on the punch press, and the mechanism associated therewith.

Fig. 3 is a sectional view taken substantially on the line 3—3 of Fig. 2.

Fig. 4 is a sectional view, somewhat enlarged, 45 taken substantially on the line 4—4 of Fig. 2.

Fig. 5 is an enlarged central sectional view of 50 the final assembly die in closed position.

Fig. 6 is a similar view of the same in open 55 position.

In carrying out the invention, a die plate 10 is secured to the bed 11 of the punch press 12. A can end feeding unit is mounted on the plate 10 and includes posts 13 adapted to receive between them a stack of can ends 14.

Also mounted on the plate 10, is a chute 15 through which the valve bodies 16 are fed. The bed 11 is inclined at an angle of approximately 45° to facilitate the feeding of the can ends and valve bodies by gravity and the removal of 5 the finished ends from the machine.

The power shaft of the punch press is provided at one end with a crank or eccentric 17 having a pin 18 with a pitman 19 connected thereto and adapted to operate the feeding mechanism here- 10 after described. In the course of this operation, a can end 14 is first fed to station A, where the central dome portion thereof is treated with oil, glycerine or the like. It is next fed to station B, where the valve body 16 is placed therein. 15 It is then fed to station C, where it is crimped to secure the valve in place, after which the completed end is released from the machine.

The length of the pitman 19 may be adjusted 20 at 20 to adjust the position of the feeding mechanism, and the length of the throw may be ad- 20 justed by adjusting the pin 18 longitudinally in the slot 21.

For actuating the feeding mechanism, the lower end of the pitman 19 is connected by a 25 pin 22 to one end of a bell crank 23, which is pivotally mounted at 24 on a bracket 25 secured to the die plate 10. The other end of the bell crank 23 is connected by a pin 26 to one end of a link 27, the other end of which is connected 30 at 28 to a slide 29 mounted in a slideway 30 secured to the plate 10.

The stack of can ends 14 is normally supported by movable lugs 31 at the base of the 35 posts 13. A link 32 is connected at one end by a pin 33 to the slide 29 and is connected at its other end by a pin 34 carried by an arm 35 pro- 40 jecting from the usual ring which operates the lugs 31, each time the slide 29 is reciprocated, to release one can end and permit it to slide down 45 a chute 40 to station A. This mechanism for releasing the can ends is of the same general type as that disclosed in the patent to George Flook, #1,864,422, issued June 21, 1932. The arm 35 is protected by a housing 41 which is se- 50 cured to the plate 10 and is provided with an arcuate slot 42 through which the pin 34 extends.

The can end is advanced by successive steps 55 from station A to station B and thence to sta- 55 tion C by a carriage 43, which reciprocates in a slideway 44. A pin 45, secured to this carriage, extends downwardly through a slot 46 in the bot- 60 tom of the slideway and is connected by a link 47 to the end of an arm 48, which is secured to the lower end of a rock shaft 49 journaled in an arm 55

50 projecting from the die plate 10. An arm 51, secured to the upper end of the rock shaft 49, is connected to the slide 29 by a link 52, so that the reciprocation of the slide 29 causes a corresponding reciprocation of the carriage 43. The length of the link 52 may be adjusted by means of a turnbuckle 53, in order to adjust the travel of the carriage 43 to the proper distance.

It will be understood that when a can end is 10 delivered to station A, it is immediately in front of a dog 54, which is pivotally mounted on the carriage 43 and held normally in raised position by a spring 55. After the required operation has been completed at station A, the carriage advances 15 the can end along the track 56 to station B. As the carriage is retracted, the spring 55 yields and allows the dog to pass beneath the next can end, which has in the meantime been delivered to station A.

20 The can end is accurately centered at station B by spring held pins 57 which engage the edge thereof at one side of the track 56, while the opposite edge is frictionally engaged by a shoe 58, which is yieldingly held by a spring 59. Upon the 25 next advance of the carriage 43, a second dog 60, yieldingly held by a spring 61, engages and advances the can end from station B to station C, while the next can end is advanced from station A to station B.

30 The mechanism for performing the various operations on the can ends at the respective stations will now be described. This mechanism is actuated by a ram 62, shown in broken lines in Fig. 3 and reciprocated in the usual manner.

35 A sight feed oiler 63 is carried at the upper end of a drip tube 64 which is reciprocably mounted in a bearing 65 located directly above station A on a bracket 66 secured to the plate 10. The lower end of the tube carries a pad 67. A rock shaft 68, 40 mounted in a bearing 69 formed on the bracket 66, has at one end an arm 70 engageable by a pin 71, which is adjustably mounted in a bracket arm 72 secured to the ram 62. A cross arm 73 at the other end of the rock shaft 68 has at one end a 45 spanner 74 with opposed pins 75 which engage a groove 76 located circumferentially of the drip tube 64. The other end of the cross arm is connected by a tension spring 77 to a fixed point on the plate 10. Thus it will be understood that 50 when the ram 62 descends, the pad 67, which is saturated with oil, glycerine or the like, moistens the dome-shaped center of the can end and, when the ram is retracted, the spring 77 restores the oiler to its initial position. This oiling of the 55 can end prevents the rubber in the valve from subsequently sticking thereto when gas is passing out of the can and also forms a tight seal to prevent passage of air into the can if any vacuum should be created on the inside thereof.

60 Directly above station B, a plunger 78 is mounted for vertical reciprocatory movement in a bearing 79 formed in a bracket 80 secured to the plate 10. The plunger 78 has an enlarged elongated head 83 formed thereon. A pin 81 65 adjustably mounted in the bracket 72 strikes the upper end of the plunger, forcing it downwardly, as the ram 62 descends. A spring 82 returns the plunger to its initial position, as soon as the ram is retracted.

70 The valve bodies 16, with the valves previously assembled thereon, descend by gravity down the chute 15, until they strike the plunger head 83 which acts as a stop for their movement down the chute. As the plunger rises, the foremost valve 75 passes beneath the plunger head and is engaged

by the dogs 84 yieldingly held by the springs 85 until the plunger descends and forces the valve body into the recess provided therefor in the can end, as shown in Figs. 3 and 4. The movement of each succeeding valve is arrested by the plunger head 83 until the cycle of operation is performed and the plunger head rises to permit another valve to pass beneath the same. When the plunger is retracted, the can end with the valve body therein is advanced to station C by the dog 60 while the dog 54 advances the next can end to station B and the succeeding valve body is advanced into the seat 83. As the carriage 43 is retracted, the spring 61 yields to permit the dog 60 to pass beneath the can end now centered at station B.

At station C the can end, here designated as 14^c, with the valve therein, is centered above a lower die 90 secured to the plate 10 and beneath an upper die 91 secured directly to the ram 62. The base of the die 90 is centrally secured to the plate 10 by a machine screw 92. This base is formed with a central boss 93, about which an annulus 94 is disposed with a peripheral shoulder 95. About this annulus a retaining ring 96 is secured by machine bolts 97 to the base of the die 90 and is formed with an internal shoulder 98 adapted to engage the shoulder 95 and limit the upward movement of the annulus 94 under the influence of springs 99 seated therebeneath.

The upper die 91 carries a plunger 100 which is reciprocably mounted in a cylindrical recess 101. A retaining ring 102, secured to the die by machine bolts 103, has an internal shoulder 104 which is engaged by the peripheral shoulder 105 of the plunger, when the latter is in raised position, by reason of the pressure of a spring 106 seated in the recess 101. When the plunger is thus seated, an annular flange 107, which defines a circular recess 108 therein, projects below the ring 102.

As the die 91 descends, the recess 108 receives the crowned center of the valve body and the peripheral flange of the body is engaged by the flange 107 of the plunger and forced into the recessed can end, designated 14^c in Figs. 5 and 6. At the same time, the elastic valve disk is stretched over the perforated dome-shaped center of the can end. The spring 106 is compressed by the resistance offered to the descent of the plunger 100 and the metal of the can end is crimped over the peripheral flange of the valve body by the joint action of the beveled edge of the boss 93 and the undercut beveled edge of the ring 102 adjacent the flange 107. Notches 109 are also provided in the lower die to form channels 110 in the can end 14^c about the edge of the valve body for permitting the escape of gases released by the valve.

It will be noted that depending pawls 111 are 60 pivotally mounted at 112 on the die 91 within keepers 113 and are normally held vertically by springs 114. As the upper die descends, the pawls pass into recesses 115 at the sides of the lower die and the inclined edges 116 of the pawls ride over the edge of the can end. When the upper die is retracted, the teeth 117 engage and lift the completed can end from the lower die, so that it drops from the teeth 117 to the inclined face of the bed, over which it slides by gravity and is 65 discharged from the machine while the next can end is advanced to position C.

From the foregoing description, it will be understood that the operation of the machine is wholly automatic. The stack of can ends 14 is 70 75

released one by one and fed by gravity through the chute 40 to station A. This feeding takes place during the retraction of the ram 62. Upon the next descent of the ram this can end is 5 treated by the oiling pad 67.

During each retraction of the ram, a can end is also advanced by the carriage 43 from station A to station B and a valve body is fed by gravity and centered over the same. At the same time, 10 the carriage 43 advances a can end from station B to station C, while the previously completed can end at station C is discharged. While the can end at station A is oiled, the same stroke of the ram places the valve in the recessed can end at 15 station B and at the same time crimps the can end at station C to secure the valve therein.

Although I have described in detail the construction and operation of the machine in its present embodiment, it is to be understood that 20 this is only for the purpose of illustration and that the invention also embraces all such modifications as may be made therein without departing from the scope of the appended claims.

Having thus described the invention, what I 25 claim as new and desire to secure by Letters Patent is:—

1. An assembling machine comprising means for feeding can ends one by one, the can end being previously formed with a central valve seat, 30 means for applying an oily substance to the valve seat, means for subsequently inserting a valve in the seat, and means for crimping the metal of the can end about the edge of the valve body to secure it in such position.

2. An assembling machine comprising a reciprocable ram, means operable in synchronism with the ram to advance previously prepared can ends formed with valve seats one by one successively to several stations during successive retractions 40 of the ram, means for centering a previously prepared valve body over each can end, and means operable by the active stroke of the ram to apply an oily substance to the valve seat at one station, to force the valve body against the valve seat at another station and to crimp the metal 45 of the can end about the edge of the valve body at a succeeding station.

3. The combination with the power shaft of a punch press having a pitman and a ram operable by said shaft, of means operable by said pitman to feed can ends formed with countersunk 50 valve seats one by one and to center a previously prepared valve body over each valve seat, and means operable by said ram to secure the valve body against the seat.

4. The combination with the power shaft of a punch press having a pitman and a ram operable by said shaft, of means operable by said pitman to feed can ends formed with countersunk 60 valve seats one by one and to center a previously prepared valve body over each valve seat, and means operable by said ram to crimp the metal of the can end about the edge of the valve body to secure the same against the seat.

5. The combination with the power shaft of a punch press having a pitman and a ram operable by said shaft, of means operable by said pitman to individually feed can ends with previously 65 formed countersunk valve seats and to center a previously prepared valve body over the valve seat in each can end, and means operable by said ram to force the valve body into the seat and to crimp the metal of the can end over the rim of the valve body to secure the same to said seat.

6. The combination with the power shaft of a

punch press having a pitman and a ram operable by said shaft, of means operable by said pitman to individually feed can ends with previously formed valve seats to a plurality of successive stations and to center a previously prepared valve body over the valve seat in each can end as it arrives at the second station, and means operable by the ram to apply an oily substance to the valve seat at the first station, to force the valve body into its seat at the second station and to crimp the metal of the can end over the rim of the valve body at a subsequent station. 5

7. The combination with the power shaft of a punch press having a pitman and a ram operable by said shaft, of a reciprocable slide operable by said pitman, means actuated by the movement of the slide in one direction to feed a can end formed centrally with a valve seat step by step to a plurality of stations and to center a valve over the can end at one of said stations, and means actuated by the ram, during the movement of the slide in the opposite direction, to force the valve against the valve seat at one station and to crimp the metal of the can end about the edge of the valve at another station. 10

8. The combination with the power shaft of a punch press having a pitman and a ram operable by said shaft, of a reciprocable slide operable by said pitman, means actuated by the movement of the slide in one direction to feed a can end 15 having a perforated recess step by step to a plurality of stations and to center a valve over the can end at the second station, means actuated by the ram to apply an oily substance to the bottom of the recess in the can end during its 20 dwell at the first station, and means also actuated by the ram to force the valve into the recess in the can end during its dwell at the second station and to crimp the metal of the can end about the edge of the valve during its dwell at a 25 third station.

9. In an assembling machine, upper and lower dies, a reciprocable ram to which the upper die is secured, means for centering between the dies a can end with a central valve seat and a valve 30 seated thereon, the lower die being provided with a yieldable annulus about the position occupied by said valve seat when thus centered, the upper die being provided with a yieldable center with a downwardly projecting peripheral flange engageable with the rim of the valve body, means to operate the ram to force the dies together, and means cooperating with said peripheral flange to crimp the metal of the can end about the rim 35 of the valve body. 55

10. In an assembling machine, upper and lower dies, a reciprocable ram to which the upper die is secured, means for centering between the dies a can end with a central valve seat and a valve seated thereon, means to operate the ram 40 to force the dies together, means cooperating with the meeting faces of the dies to crimp the metal of the can end about the rim of the valve body, and pawls carried by the upper die and engageable with opposite edges of the can 45 end to discharge the same as the ram is retracted.

11. In an assembling machine, upper and lower dies, a reciprocable ram to which the upper die is secured, means for centering between the dies a can end with a central valve seat and a valve seated thereon, the lower die being provided with a yieldable annulus about the position occupied by said valve seat when thus centered, the upper die being provided with a yieldable center 50 70 75

- with a downwardly projecting peripheral flange engageable with the rim of the valve body, means to operate the ram to force the dies together, means cooperating with said peripheral flange 5 to crimp the metal of the can end about the rim of the valve body, and pawls carried by the upper die and engageable with opposite edges of the can end to discharge the same as the ram is retracted.
10. An assembling machine comprising means for feeding can ends one by one, the can ends being each previously formed with a central recess having a dome-shaped bottom with a hole therein, means for centering a valve body over each can end, the valve body being in the form of a cap with an elastic disk constituting its inner face, and means for securing the valve body within the recess in the can end with the elastic disk stretched over the hole in the dome.
15. An assembling machine comprising means for feeding can ends one by one, the can ends being each previously formed with a central recess having a dome-shaped perforated bottom, means for positioning in the recess of each can 20 end a previously prepared valve body consisting of a cap with an elastic disk constituting its inner face, the elastic disk being stretched over the dome-shaped bottom of the recess when the valve is thus positioned, and means for crimping 25 the metal of the can end over the edge of the valve body to secure it in such position.
14. An assembling machine comprising means for feeding previously prepared can ends singly step by step, the can ends being each formed with a central recess having a dome-shaped perforated bottom, means for centering over the recess of each can end a previously prepared valve body 30 consisting of a cap with an elastic disk constituting its inner face, a reciprocable ram, means carried by the ram to secure the valve body in the recess of the can end with the disk stretched 35 over the dome-shaped bottom thereof, and synchronizing means to cause the advance of the can end and valve body to take place while the ram is being retracted.
15. An assembling machine comprising a reciprocable ram, means operable in synchronism with the ram to advance previously prepared can ends one by one successively to several stations during successive retractions of the ram, the can ends being each formed with a central recess having a dome-shaped bottom with a hole therein, means for centering over the recess of each can end a previously prepared valve body 40 consisting of a cap with an elastic disk constituting its inner face, and means operable by the active stroke of the ram to force the valve body into the recess at one station and at a subsequent station to crimp the metal of the can 45 end about the rim of the valve body with the disk stretched over the hole in the dome-shaped bottom of the recess.
16. The combination with the power shaft of a punch press having a pitman and a ram oper-

able by said shaft, of means operable by the pitman to feed one by one can ends which have each been previously formed with a central recess having a dome-shaped perforated bottom, and to center over each can end a valve body in the form of a cap with an elastic disk constituting its inner face, and means operable by the ram to secure the valve body within the recess in the can end with the elastic disk stretched over the perforated dome.

17. The combination with the power shaft of a punch press having a pitman and a ram operable by said shaft, of means operable by said pitman to feed one by one can ends which have each been previously formed with a perforated central recess and to center a previously prepared valve body within the recess of the can end, and a die carried by the ram and having a yieldable circular element insertable within the wall of said recess and into clamping relation to the rim of the valve body as the ram descends, and means on the die to crimp the metal of said wall over said rim.

18. The combination with the power shaft of a punch press having a pitman and a ram operable by said shaft, of means operable by said pitman to individually feed can ends with previously formed countersunk valve seats and to center a previously prepared valve body over the valve seat in each can end, and a die carried by the ram, said die having a yieldable center insertable in the valve seat and at the same time engageable with the rim of the valve body to force it against the seat, said die also having means to crimp the metal of the can end over the rim of the valve body to secure the same as it is held against the seat.

19. The combination with the power shaft of a punch press having a pitman and a ram operable by said shaft, of means operable by said pitman to feed can ends formed with countersunk valve seats one by one and to center a previously prepared valve body over each valve seat, and means operable by said ram to crimp the metal of the can end over the rim of the valve body to secure the latter to its seat and at the same time to form radial channels to permit gases released by the valve, when the can end is secured to a can body, to escape to the atmosphere.

20. In an assembling machine, upper and lower dies, a reciprocable ram to which the upper die is secured, means for centering between the dies a can end with a central valve seat and a valve seated thereon, means to operate the ram to force the dies together, and means co-operating with the meeting faces of the dies to crimp the metal of the can end about the rim of the valve body and at the same time to form radial channels to permit gases released by the valve, when the can end is secured to a can body, to escape to the atmosphere.

ALFRED L. KRONQUEST.
